UNITED STATES PATENT OFFICE.

GEORGE W. DECKER, OF CANANDAIGUA, NEW YORK.

CLOTHES-DRIER.

SPECIFICATION forming part of Letters Patent No. 299,523, dated June 3, 1884.

Application filed September 5, 1883. (No model.)

To all whom it may concern:

Be it known that I, GEORGE W. DECKER, a citizen of the United States, residing at Canandaigua, in the county of Ontario and State 5 of New York, have invented a new and useful Clothes-Drier, of which the following is a specification, reference being had to the accompanying drawings.

This invention relates to clother-driers; and 10 it has for its object to provide means possessing superior advantages in point of simplicity, durability, convenience, inexpensiveness, and general efficiency.

To this end it consists in certain details of 15 construction and combination of parts, as hereinabove set forth, and particularly pointed out in the claims.

In the accompanying drawings, Figure 1 is 20 a perspective view of my improved clothes-drier opened and ready for use. Fig. 2 is a similar view of the same closed up. Fig. 3 is a vertical section of Fig. 1. Fig. 4 is a horizontal section on the line xx , Fig. 3.

Like letters refer to corresponding parts in 25 the several figures.

Referring to the drawings, A designates the head, carrying the clothes-drying arms, and provided at its lower portion with a circular socket or opening, B, by means of which it is 30 mounted on the standard C, projecting from a suitable base, D, the standard being formed circular in cross-section, so that the head can freely revolve thereon. The head is preferably constructed of the shape shown in the drawings— 35 that is, having four sides or faces, a —each of said sides or faces being formed with a vertical slot, E, and in the rear of the slots is a recess, F, the latter being arranged above the bottom wall of the slots, so that a shoulder, e , is formed 40 between it and the said bottom wall. As stated, each of the sides or faces a is provided with the above-described arrangement of slots and recesses, a similar number of arms, G, having an elongated slot, g , at the inner ends, being 45 pivoted in the slots E by means of a bolt, H, which passes longitudinally through and parallel with the sides of the head, extending across the slots E and through the elongated slots g of the arms G, a nut, I, serving to secure the bolt in position. The inner ends of 50 the arms are slightly inclined, so as to more tightly fit the recesses F when extended for use.

A cord or rope, J, is fastened to one of the arms at its inner portion, and passes through eyes c in each of the other arms at or about 55 the same distance from the head. When the rope reaches the arm from whence it started, it is passed through an eye therein, and extends along the length of said arm a short distance, and when a sufficient space has been 60 left between it and the preceding rope it is passed through the said arm in a reverse direction from whence it started, and again circles the arms at equal distances from the center of the head. This manner of twining the 65 rope is kept up to the end of the arms, grooves K being formed at the ends of the arms, in which loops L of the rope J are fitted, pins or studs i being passed through the outer ends of the arms, so as to hold the loops when the latter are passed around the same. It will be 70 seen that the above-described manner of securing and twining the rope is very efficient, and since the rope is passed loosely through the eyes the strain on any one point of the 75 drier will cause the rope to slip, so as to tug on the remaining arms, and thus distribute the strain.

The operation of my invention can be readily understood from the foregoing description, 80 taken in connection with the annexed drawings: In the closed position, (shown in Fig. 2,) the bolt H is in the upper part of slot g , so that in order to lower said arms it will be necessary to slightly raise the arms, and then they can 85 be extended, as shown in Fig. 1, the inner inclined end of the arms fitting in the recesses F and resting on the shoulders e , so that said arms will be securely held from displacement, while they can be readily raised by drawing 90 the arms out of the recesses, and then raising them in the usual manner.

The advantages of my invention are obvious, the construction being simple and durable, while the operation and arrangement are convenient and efficient. The movements of the arms can be performed with rapidity, and they will immediately assume the correct positions, as shown.

Since all the parts except the bolts and nuts 100 are constructed from wood, the drier will not be coated with rust or other matter common to iron, and thus the clothes will not be in danger from soiling from this cause. The head being

constructed from a solid piece of wood, and provided with bolts passing through the same each way, and also with a band at its lower end, if found necessary, said head will be 5 strongly held together, and will be prevented from splitting.

It will be seen that two or more of the arms can be extended in the position shown in Fig. 1, when it is only necessary to hold a few 10 clothes, and can be readily folded up against the face of the head, if occasion should require it.

It will be obvious that various modifications can be resorted to in the foregoing without departing from the spirit or scope of my invention, and I wish it understood that I do not 15 limit myself to the number of the arms for holding the clothes.

Having described my invention, I claim as 20 new—

As an improvement in clothes-driers, a standard, C, in combination with the head A, provided at its lower end with a socket loosely fitting the upper end of the standard, and having sides or faces a, each of which is formed with 25 vertical slots E, recesses F in the rear of the slots, and arranged above the bottom wall of the same, thereby forming shoulders e, the arms G having an elongated slot at the inner end, and bolts passing through the head and arms within 30 the slots, the said bolts being located as shown, whereby the arms may be held in an extended or a vertical position, as set forth.

In testimony that I claim the foregoing as my own I have hereto affixed my signature in 35 presence of two witnesses.

GEORGE W. DECKER.
